UNITED STATES PATENT OFFICE.

EZRA E. CLARK, OF NEWTONVILLE, MASSACHUSETTS.

SPRINKLER-HEAD.

1,318,543.

Specification of Letters Patent. Patented Oct. 14, 1919.

Application filed January 16, 1919. Serial No. 271,379.

To all whom it may concern:

Be it known that I, EZRA E. CLARK, a citizen of the United States, residing at Newtonville, county of Middlesex, State of Massachusetts, have invented an Improvement in Sprinkler-Heads, of which the following description, in connection with the accompanying drawing, is a specification, like characters on the drawing representing like parts.

This invention relates to sprinkler heads of that known type which comprises a body having a discharge port and a yoke portion carrying a valve for the discharge port, two strut members in the form of a toggle for normally holding the valve closed and each provided with an arm and a fusible link connection between said arms for maintaining normally the strut members in their operative position.

In many sprinkler heads of this type the construction is such that the stress on the fusible link due to holding the valve to its seat is a pulling or tension stress.

It is the principal object of my present invention to provide an improved sprinkler head of this type which is so constructed that the stress on the fusible link will be a compression stress rather than a pulling or tension stress. As a result it is possible to employ a fusible link having a simpler construction than is required where the link is subjected to a pulling stress. I accomplish this herein by so arranging the arms extending from the toggle members that they cross each other whereby the buckling or collapsing movement of the toggle members will cause the ends of the arms to move toward each other. The fusible link is constructed to be placed between the ends of the arms and acts as a strut member to hold them separated and thus hold the valve closed.

In order to give an understanding of my invention, I have illustrated in the drawings a selected embodiment thereof which will now be described, after which the novel features will be pointed out in the appended claims.

Figure 1 is a side view of a sprinkler head embodying my invention;

Fig. 2 is a section on the line 2—2, Fig. 1;

Fig. 3 is a fragmentary view showing

the toggle strut members with their crossing arms.

Fig. 4 is a section on the line 4—4, Fig. 1, with the fusible member omitted.

The body of the sprinkler head is shown at 1 and may have any suitable or usual construction. It is provided with the usual exteriorly screw-threaded portion 2 which is adapted to be connected to the water pipe of the sprinkler system and which is formed with the usual discharge opening 3 that is normally closed by the valve 4. The body 1 is also shaped to present the yoke portion 5 which carries at its upper end a screw 6 having the deflector 7. The valve 4 is normally held to its seat by two strut members 8 and 9 which engage each other at 10 and which have a toggle action, the strut member 9 bearing against the valve 4 and the strut member 8 bearing against the screw 6.

The parts thus far described are or may be all as usual in sprinkler heads of this type and form no part of my present invention.

In sprinkler heads of this type the toggle strut members 8 and 9 are frequently provided with laterally-extending arms which are connected by a fusible connection, the latter normally holding the toggle members in their operative position, as shown, but becoming fused and thereby liberating the strut members 8 and 9 and allowing the valve 4 to be unseated when the temperature rises above a predetermined point.

In my invention the strut members 8 and 9 are provided with the arms 11 and 12, respectively, with which a fusible link 13 co-operates to hold the strut members in their operative position. The arms 11 and 12, however, are shaped so that they have a crossed relation whereby the end 14 of the arm 11 extending from the upper strut member 8 is situated below the end 15 of the arm 12 extending from the lower strut member 9. The fusible link 13 is situated between the ends 14 and 15 of the arms and thus normally holds the strut members in their operative position.

Because of the crossed relation of the arms 11 and 12, the pressure of the valve against the strut members 8 and 9 will tend to cause the ends 14 and 15 of the arms to

move toward each other and hence the fusible link 13 will be subjected to a compression stress.

This fusible link 13 may have any suitable construction. I have herein shown it as comprising two plates 16 and 17 which are connected by suitable fusible material 18. The two plates 16 and 17 overlap each other and the plate 17 is provided with the offset portion 19 thereby to form a shoulder against which the lower end of the plate 16 rests. The offset of this portion 19 and the manner in which the plate 16 engages it is such as to produce a leverage by which the compression stress will tend to swing the plates relative to each other about the lower edge of the plate 16 as an axis and thus separate said plates, such tendency being resisted by the fusible material 18. The upper edge of the plate 16 is shown as having a notch 20 therein in which the end 15 of the arm 12 is received and the offset portion 19 of the plate 17 is also provided with a recess 21 in which the end 14 of the arm 11 is received. The ends 14 and 15 of the arms 11 and 12 are also shown as having notches 22 therein in which the edges of the fusible link are received. Because of the fact that the link 13 is subjected to compression stress rather than to pulling or a tensile stress, the construction of the link is simplified.

Owing to the fact that the arms 11 and 12 have a crossed relation, it will follow that when the fusible link gives way, the pressure of the valve against the toggle struts will cause the ends of the arms to move toward each other, as seen in dotted lines, Fig. 3. In order that these arms may not strike each other and thus become locked, I will preferably so arrange them that their movement toward each other takes place in different vertical planes. The strut members 8 and 9 are each shown as having a triangular shape, and they are arranged with their sides 10 engaging each other and with their apices engaging the screw 6 and valve 4, respectively. The sides 10 constitute the axis about which they turn when they buckle after the fusible link has given way.

Looking at Figs. 1 and 4, the arm 11 extends from the upper strut member 8 at the left-hand edge thereof while the arm 12 extends from the lower strut member 9 at the right-hand edge thereof, and both arms are bowed somewhat and are so designed that their ends 14 and 15 are located substantially over each other, although I have shown the end 15 of the arm 12 as situated slightly to the right of the end 14 of the arm 11 so as to avoid any possibility of the arms striking each other when the link gives way.

By means of the construction shown the

arms 11 and 12 are separated sufficiently so that there is no danger of their becoming corroded together, thus rendering the device inoperative.

I claim:

1. In a sprinkler head of the type having a body provided with a discharge opening, a valve for closing said opening, and toggle elements for holding the valve closed, the combination with said toggle elements, of an arm extending from each element, said arms having a crossed relation with the ends extending beyond the crossing point, and a fusible member interposed between the ends of the arms and subjected normally to a compression stress.

2. In a sprinkler head of the type having a body provided with a discharge opening, a valve for closing said opening, and toggle elements for holding the valve closed, the combination with said toggle elements, of an arm extending from each element, said arms having a crossed relation and occupying different vertical planes, and a fusible member interposed between the ends of said arms.

3. In a sprinkler head of the type having a body provided with a discharge opening, a valve for closing said opening, and two toggle strut members for holding the valve closed, the combination with said strut members, of an arm extending from each member, the end of the arm extending from the lower member being situated above the end of the arm extending from the upper member, and a fusible member interposed between the ends of said arms.

4. In a sprinkler head of the type having a body provided with a discharge opening, a valve for closing said opening, and upper and lower toggle strut members for holding the valve closed, the combination with said strut members, of an arm extending from one side of the upper member, another arm extending from the opposite side of the lower member, said arms having a crossed relation so that the end of the first-named arm is situated below the end of the other arm, and a fusible member interposed between the ends of the arms.

5. In a sprinkler head of the type having a body provided with a discharge opening, a valve for closing said opening, and upper and lower toggle strut members for holding the valve closed, the combination with said strut members, of an arm extending from one side of the upper member, another arm extending from the opposite side of the lower member, said arms being bowed and having a crossed relation so that the end of the first-named arm is situated below the end of the other arm, and a fusible member interposed between the ends of said arms.

6. In a sprinkler head of the type having a body provided with a discharge opening,

a valve for closing said opening, and toggle elements for holding the valve closed, the combination with said toggle elements, of an arm extending from each element, said arms having a crossed relation, and a fusible member interposed between the ends of the arm and subjected normally to a compression stress, said member comprising two overlapping plates, one of which has a shoulder against which the edge of the other plate rests, and fusible material connecting said plates.

7. In a sprinkler head of the type having

a body provided with a discharge opening, a valve for closing said opening, and toggle elements for holding the valve closed, the combination with said toggle elements, of an arm extending from each element, said arms having a crossed relation with the crossing point situated between the toggle elements and the ends of the arms, and a fusible member interposed between said ends.

In testimony whereof I have signed my name to this specification.

EZRA E. CLARK.
